Fig. 1. Schematic diagram of a tunnel conveyor system with various control and monitoring components.

The diagram illustrates a tunnel conveyor system (C) with the following components and their connections:

- Left Tunnel:** Features a **DOOR** and a **THERMOMETER** (THERMOMETER INDICATOR).
- Central Tunnel:** Features a **DOOR** and a **THERMOMETER** (THERMOMETER INDICATOR).
- Right Tunnel:** Features a **DOOR** and a **THERMOMETER** (THERMOMETER INDICATOR).
- Conveyors:** A **CONVEYOR** (Y) and a **CONVEYOR** (Y') are shown.
- Humidification:** A **HUMIDIFIER** is connected to the system.
- Heating:** A **HEATER** is connected to the system.
- Fan System:** A **FAN** (F) is connected to the system.
- Control and Monitoring:**
  - Thermostats:** **THERMOSTAT** (E) and **THERMOSTAT** (G) are connected to the system.
  - Air Speed Indicators:** **AIR SPEED INDICATOR** (21) and **AIR SPEED INDICATOR** (22) are connected to the system.
  - Humidity Indicators:** **HUMIDITY INDICATOR** (A) and **HUMIDITY INDICATOR** (B) are connected to the system.
  - Duct Thermometers:** **DUCT THERMOMETER** (X) and **DUCT THERMOMETER** (Y) are connected to the system.
  - Conduit:** **CONDUIT** (F) is connected to the system.
  - Operatives:** **OPERATIVES** (C) are shown at the far right.

DRYING METHOD

Application filed February 20, 1925. Serial No. 10,578.

A method of drying leather which will save time required when, as is now the common practice, the leather is permitted to dry naturally, either in an ordinary room or in 5 the open air outside the building, and which will be practicable for the drying of the leather on a large commercial scale and without injuring the structure of the leather, will in the nature of things introduce a very important economy in the leather art. This 10 is especially true in the manufacture of shoes, the production of which involves a multiplicity of different operations and must be carried out on a large commercial scale in 15 order to be economical and hence commercially successful. In the manufacture of shoes it is essential that the soles be in a wet condition, in order that they may be soft and pliable, when applied to the uppers, while 20 subsequent operations require that the soles be dry while these operations are being performed. One step in the manufacture of shoes therefore consists in the wetting of the soles prior to their application to the 25 upper and another step consists in the drying of the soles after they have been so applied. While this drying operation has been herein referred to as a step in the manufacture of shoes it is as a matter of fact now 30 universally or substantially universally performed merely by permitting the soles to be dried naturally, the racks containing the partially completed shoes being simply pushed to a space or place provided or available therefor in the factory and allowed to 35 remain there until the operatives consider the soles to be sufficiently dry for the subsequent operations. The time required for this drying operation varies, and is controlled in 40 part by atmospheric conditions, a longer time being necessary, for example, in wet weather than in dry weather. The variation in time, in fact, is very considerable, ranging from about three days to about twelve days. During 45 all of this time the lasts are in partially formed shoes.

It, therefore, follows (1) that a large extent of floor space must be devoted to the storage of the shoes while undergoing the 50 natural drying operation; (2) that a very

large number of racks are required for the transfer of the shoes to and away from the drying room or space and for the storage of the shoes while being dried, since the racks retain the shoes during the entire drying period; (3) that considerable manual labor is involved in and considerable aisle space required for, the transfer of the racks to the drying room or space and from the drying room or space to the machine where the next operation in the manufacture of the shoes is performed; (4) that a very large supply of lasts is required owing to the slow turnover in the use thereof, since each last, as already stated, necessarily remains in the shoe being formed upon it during the entire drying operation as well as during the previous operations and several of the subsequent operations.

Notwithstanding these well recognized 70 disadvantages the drying of the soles naturally has been retained as the common practice owing to the fact that artificial drying has not been attended with much success owing to the peculiarity of leather which if suddenly deprived of moisture is broken down in structure, becomes brittle and loses its tensile strength, so that it cracks when bent. A shoe having a sole of such nature would 75 give no service.

Although more particularly intended for the drying of the soles of shoes in the process of manufacture of the shoes, it is not our intention to limit its application to the drying of such articles, since we realize that it may 80 be usefully employed in the drying of many things, especially leather products of different kinds. For example, it may be very usefully employed to dry hides as they come 85 from the tanning baths.

A most important purpose of this invention, therefore, is to eliminate the disadvantages incident to the natural drying of leather without injuring the structure of the leather as compared with that dried naturally under 90 most favorable conditions. To this end the invention broadly comprehends a process by which the leather undergoing treatment is subjected progressively to rapidly flowing currents of heated humidified air and heated 95 100

substantially dry air artificially produced and whose speed of flow, humidity and temperatures are controllable in accordance with the requirements of the particular leather under treatment, whereby the leather thus subjected to these controlled atmospheric conditions is dried from the inside outward in a comparatively short space of time.

The invention further comprehends:—

(1) The passage of the articles being dried through a rapidly flowing current of heated and humidified air having what may be referred to as zones of different temperatures, whereof the temperature of the heated humidified air is lower at the place where the articles are first subjected to this step of the process and also at the place where this step is completed than in the intermediate zone;

(2) The passage of said articles then progressively through a rapidly flowing current of substantially dry heated air similarly having what may be referred to as zones of different temperatures, the temperature of this air being higher at the middle than at either end;

(3) The admission of the humidified and heated air at a plurality of different places with relation to the travel of the articles under treatment through the zone or zones of such air;

(4) Similarly the admission of the substantially dry heated air at a plurality of different places with relation to the travel of the articles under treatment through the zone or zones of substantially dried air;

(5) The retempering of the leather by subjecting it to the action of humidified air immediately at the conclusion of its travel through the zone or zones of substantially dry heated air.

No arbitrary rule as to the percentage of humidity, the degrees of temperature or the velocity of the airs, or the length of time during which the leather is subjected to these airs can be laid down, as these depend upon variable conditions. Recognizing, therefore, that the humidity, temperature, velocity of the airs and the length of time to which the leather is subjected thereto in carrying the process into practice will be dependent upon variable conditions and reserving to ourselves the right to employ any such which are capable of giving satisfactory results, we would state that in the practicable application of the process in the manufacture of shoes upon a very large commercial scale perfect results have been secured from the following procedure which is being practiced, to wit:

The shoes are first passed through a current of air whose temperature varies in different portions of its length being approximately 80-85 degrees F. at its ends where the shoes enter and leave the current and approximately 90-95 degrees F. at the parts of the

current intermediate its ends, and whose relative percentage of humidity is approximately 70-75 and having a velocity of from about 5000 to 8000 feet per minute. The duration of this step of the process depends upon the style of shoe and character of material, about one and one-half hours being usually sufficient to dry the leather from the inside, leaving it in such shape that remaining moisture can be driven off in a dry temperature without injury to the leather. The next step consists in passing the shoes through a current of substantially dry air increasing in temperature from about 120 or 125 degrees F. at its end where the shoes enter it to about 140-145 degrees F. and then decreasing to 120-125 degrees F. at its end where the shoes leave it, and having a velocity of from about 5000 to 8000 cubic feet per minute. The velocity of the airs should be determined in accordance with the condition of the leather and the humidity and temperature of the air. The duration of time of the second step usually is about one and one-half hours. The times herein mentioned are especially applicable to welt shoes, nailed shoes requiring less time.

Experience has demonstrated that the drying of the shoes by this process has resulted in a product which is equal in all respects to those dried naturally under most favorable conditions, and in fact is attended with far less danger than when the shoes are dried naturally in steam heated rooms, the dry air of which frequently breaks down the structure of the leather. The process further reduces the time required from many days to only a few hours, the drying of the shoes by natural atmospheric conditions or in ordinary heated rooms, as at present, requiring from about three days to about twelve days, as already stated.

It has been found to be desirable in practice to subject the shoes to humidified air while they are passing through the zone of heated dry air and after they have passed the place of highest temperature thereof. This moistens the soles and uppers to a sufficient extent to re-temper the leather and thereby place them in better condition for subsequent operations.

In the carrying out of the process on a large commercial scale the leather under treatment is moved progressively through suitable treating chambers into which the heated humidified and heated substantially dry airs are introduced at different places in the lengths of chambers, from outside sources, respectively. This provides a safeguard against over-saturation of the airs by moisture extracted from the leather, and in co-operation with the rapid change of the airs in the treating chambers causes the effective withdrawal of the moisture from the leather in a minimum of time and without

danger of breaking down the structure of the leather. The movement of the leather is preferably continuous.

If the leather under treatment is in the form of partially finished shoes, the shoes are preferably carried through the treating chamber or chambers in the racks X upon which they are transferred from operative to operative throughout all the manufacturing operations, a suitable conveyor or conveyors being employed to carry the racks from operative to operative and through the treating chamber or chambers. Figs. 1 and 2 show conventionally connected lines of conveyor Y, Y' extending continuously past a number of operative's stations, marked "Operatives," and serving to transfer the racks X from operative to operative and to the elevating conveyor Y² which carries the racks into the receiving end of the leather conditioning chamber A and delivers the same to the conveyor B which traverses said chamber. Fig. 2 shows one side of the section Y' which leads to the elevating section (the other side of said section being omitted for lack of space to show it) and also shows a lowering conveyor Y³ which extends from the rack discharging end of the tunnel A' and conducts said racks with the conditioned and partially completed shoes downward to a conveyor, whose end is indicated at Y⁴, and along which other operatives are stationed. The conveyors employed are of any nature suitable for use in this process. In an application for Letters Patent of the United States filed by us on June 7, 1924, and numbered, serially, 718,661, we have shown, described and claimed a conveyor for transferring the racks from operative to operative and to and away from the dryer, and said conveyor is particularly well adapted for use in relation to the process which forms the subject of the instant application for patent. If, on the other hand, the leather is in the form of hides as they come from the tanning vat, for example, the conveyor or conveyors may be of a suitable nature adapted to carry the hides in suspended position through the treating chamber or chambers.

An apparatus particularly well adapted to the carrying of this process into practical effect, is shown in the accompanying drawings. This apparatus embodies two chambers through which the articles to be dried are carried and within which they are subjected to the currents of heated humidified air and heated substantially dry air, respectively. These airs have their sources in suitable air heating and humidifying means, which are arranged outside of and are suitably connected to, the chambers, and suitable means cooperating with the air heating and humidifying means are provided to control the volume, speed of travel and tem-

peratures of the airs, in accordance with requirements. Two styles of conveyors traversing the chambers are illustrated, one being exemplary of a conveyor which is preferred when the article to be dried is of a kind which should be carried by a traveling bed upon which it rests and the other exemplary of a form which should be used when the article to be dried is of a kind which should be suspended while being dried. This apparatus has been made the subject of an application for patent filed in the United States Patent Office of even date herewith and numbered serially 10,577.

In the drawings illustrating the said apparatus, and in which drawings like characters of reference denote corresponding parts in the several figures:—

Fig. 1 is a side elevation.

Fig. 2 is a plan view.

Figs. 3, 3A and 3B are horizontal sectional views conjointly illustrating the apparatus; Fig. 3 being a view of the end of the apparatus at which the articles enter and leave the drier; Fig. 3A a view of the intermediate portion of the drier; and Fig. 3B a view of the end opposite the end shown in Fig. 3.

Fig. 4 is a cross sectional view on a larger scale than the preceding figures, taken through one of the tunnels and the corresponding conduit through which it receives the humidified or substantially dry air, as the case may be.

Fig. 5 is a view similar to Fig. 4 but showing a style of conveyor preferred when the articles to be dried are of a nature such that they should be carried through the drier in suspended condition.

A and A' designate two chambers, in the form of tunnels. These two tunnels may be of any suitable length and may be correlated in any manner which will enable the articles to be subjected to the various steps of the drying treatment in their travel first through one tunnel and then through the other. A very desirable arrangement is that illustrated in the drawings, which show them arranged side by side and in substantial parallelism with each other and with the entrance to the tunnel A and the exit from the tunnel A' at the same end of the apparatus and said tunnels connected with each other near said end by a transverse duct A² and having their opposite ends connected by a transverse chamber A''. It would not, however, be a departure from the spirit of the invention to arrange the tunnels in other positions relatively to each other—but the illustrated arrangement is preferred because of its comparative compactness.

The articles to be dried are moved at a suitable speed throughout the lengths of both tunnels A, A', also within the chamber A'' from the discharging end of tunnel A to the receiving end of tunnel A', by conveying

means of any suitable construction. One such means, particularly when the articles being dried are the soles of partially finished shoes, consists of three separate endless traveling conveyors B, B'' and B', arranged in tunnels A and A' and chamber A'', respectively, and gravity conveyor sections b and b', respectively arranged to transfer the articles from the discharging end of conveyor B to the conveyor B' and from said conveyor B' to the receiving end of conveyor B''. Each of the illustrated endless traveling conveyors is of that known type comprising endless side chains 10 which traverse suitable sprockets at the ends of the conveyors and are provided with rollers 11 which traverse upper tracks 12 and lower tracks 13 and with transversely extending rollers 14 which are arranged between the chains and connected thereto and conjointly form the bed of the conveyor. The tracks 11 and 12 are suitably supported above the bottom 15 of the tunnel as by suitably connected and braced upright frame-members 16 carried by the bottom wall 15 of the tunnel. This construction of conveyor is simple and practicable, since it provides a strong and yet simple traveling support for the racks X which carry the shoes undergoing the drying operation, and will not sag under the weight of said racks and shoes and may be operated with a minimum of power. It, of course, will be understood that power is applied, as is usual, to the sprockets at one end of each conveyor and that the sprockets at the other end of each conveyor are idlers and in practice are provided with suitable means to take-up slack in the conveyor. Since power and take-up means are common in the conveyor art and their application to this type of conveyor is well understood it is unnecessary particularly to illustrate the same as a part of this mechanism.

It will be understood that the particular conveyor used will be of the style and character most appropriate for the particular thing being dried. For example, instead of using the particular conveyor set forth, or any conveyor having a traveling bed to support the article being dried, it will be found desirable when hides or the like are the articles being dried to use a conveyor, marked B', of the type from which the articles being dried may be suspended, or may depend, as indicated in Fig. 5. This conveyor comprises endless traveling chains 30 and suitable means or members, indicated at 31, supported thereby and in turn supporting the hides X'. In no respect other than with relation to the conveyor is any change required in the apparatus; the tunnels and remaining elements hereinafter described being substantially the same regardless of the particular article being dried.

65. A suitable air-heating and humidifying

means C is arranged outside the tunnel A and about midway the length thereof and a suitable air heating means C' similarly is arranged outside of and about midway the length of the tunnel A'. The means C may be of any construction or type and capacity which will supply moistened air in sufficient volume and at the temperature required to subject the articles traversing the tunnel A to the treatment predetermined for said articles in said tunnel, and the means C' similarly is of any suitable construction and capacity to supply substantially dry air in sufficient quantity and at the required temperature for the treatment predetermined for the articles in their travel through the tunnel A'. Means suitable for these several purposes are known and since a particular construction thereof forms no part of this invention it is unnecessary to illustrate or further refer to any details of the source of heated humidified air or of the source of dry heated air as a part of this application. Mention, however, may be made of the fact that the source of humidified heated air which we have used with satisfactory results is a known construction of air washer or conditioner, details of which are illustrated in the hereinbefore referred to application executed by us of even date herewith.

The heated humidified air is discharged under pressure from a suitable fan D into a conduit E at about the longitudinal center of the latter. This conduit extends lengthwise of the tunnel A and from it the said tunnel receives the heated humidified air supplied by the means C. This air flows in opposite directions within the conduit from the inlet to said tunnel, the inlet portion of the conduit being provided with diverging 105 wall members such as those shown at 21 in Fig. 1 to induce such flow, and passes from the conduit into the tunnel A through ducts 20 which are suitably spaced along the lengths of the conduit and tunnel. The sections of the conduit from the inlet to the first duct on each side thereof, and from each of said ducts to the next, are respectively of lesser diameter, to compensate for the lesser volumes of the air in these sections and in order that the speed of the flow of air may be maintained. To control the supply of this air from the conduit to the tunnel at the various places at which the air is introduced into the tunnel, each section of the conduit is provided with a suitable manually operable valve or damper 22. These dampers or valves are preferably located within the ducts 20, respectively.

The heated dry air is similarly discharged from the heater C' under pressure from a suitable fan D' into a conduit E'. This conduit is like the conduit E and bears the same relation to the tunnel A' that the conduit E does to the tunnel A. Its dampers or valves

are marked 22' and the spaced ducts through which it has communication with the tunnel A' are marked 20'. It has diverging wall members 21' similar to those marked 21, at the place where it receives the heated air from the heater.

Suction fans, as indicated at F, F', are employed at the air exit ends of the tunnels to insure a rapid venting of said tunnels and in consequence a rapid change of the air therein. The fan F is preferably connected to the chamber A'' and in such operative relation to said chamber and to the tunnels A, A' that it will draw the air from the chamber A'' and hence induce a rapid flow of the air in the tunnels A, A' toward said chamber. A suitable damper or valve, as indicated at 23, is provided to control the air outlet from the casing 24 which contains this fan. The fan F' is preferably connected to the air outlet end of the tunnel A' to draw the air toward said end, and is in operative relationship with the tunnel A through the duct A² connecting the tunnels with each other at this end of the apparatus.

Therefore, it will be seen that the pressure fans D, D' and suction fans F, F' cooperate with each other in creating a rapid flow of constantly changing air in the tunnels A, A' and chamber A'' and duct A². These fans, together with provision whereby the air may be controllably introduced into the tunnels at different places in the lengths of the latter enables the operator to regulate the volume, speed of travel and temperatures of the humidified air in different parts of the tunnel A and of the dry heated air in different parts of the tunnel A', and to avoid oversaturation of the air.

A re-tempering of the dried leather to make the same sufficiently flexible for subsequent operations is made possible by the apparatus illustrated, the drawing showing a duct 30 (Fig. 2) extending to the tunnel A' from the conduit E which carries the humidified air. This duct 30 communicates with the tunnel A' at a point near the discharge end of the latter.

Each of these tunnels is preferably provided along its length with a series of doors G to afford access to its interior for testing or other purposes.

In practice, and as indicated generally or conventionally in Fig. 1 of the drawing suitable means are provided at appropriate places to show the condition with respect to speed of travel, temperature and humidity of the air in the tunnels and it is apparent that if considered to be desirable means (as indicated by the parts marked "Thermostat" in Fig. 1) may be provided to automatically control volume, speed of travel, temperature and/or humidity in accordance with a predetermined setting of said means.

Having thus described the process and a

suitable means for carrying the same into practice, what we believe to be new and claim as our invention, is:—

1. A drying process which comprehends the creation within a drier of a zone of rapidly flowing heated humidified air whose temperature at both ends of the zone is lower than that between said ends and the movement of the article to be dried through said zone. 70

2. A drying process which comprehends the creation within a drier of a zone of rapidly flowing heated substantially dry air whose temperature at both ends of the zone is lower than that between said ends and the movement of the article to be dried through said zone. 75 80

3. A drying process which comprehends the creation within a drier of a zone of rapidly flowing heated humidified air whose temperature at both ends of the zone is lower than that between said ends, the movement of the article to be dried through said zone, and the subjecting of the article thus treated to the action of a current of heated substantially dry air. 90

4. A drying process which comprehends the creation within a drier of a zone of rapidly flowing heated substantially dry air whose temperature at both ends of the zone is lower than that between said ends, and the subjecting of the article to be dried to a humid atmosphere and thereafter to the effect thereon of the said zone of substantially dry air while the article is traversing said zone. 95

5. A drying process which comprehends the subjection of the article to be dried to a humid atmosphere of increasing and decreasing temperature and then to a heated substantially dry atmosphere. 100

6. A drying process which comprehends the subjection of the article to be dried to a humid atmosphere and then to a heated substantially dry atmosphere of increasing and decreasing temperature. 105

7. A drying process which comprehends the subjection of the article to be dried to a humid atmosphere of increasing and decreasing temperature and then to a heated substantially dry atmosphere of increasing and decreasing temperature. 110 115

8. A drying process which comprehends the creation within a drier of a zone of rapidly flowing heated humidified air whose temperature is lower at the ends of the zone than at the intermediate part thereof and a separate zone of heated substantially dry air whose temperature at the ends of the zone is lower than that at the intermediate part thereof, and the movement of the article to be dried through these zones, successively. 120 125

9. A drying process which comprehends the heating and humidifying of air to substantially predetermined degrees of heat and humidity, the heating without humidification of air to a substantially predetermined degree of 130

heat and dryness, the introduction of the preheated and prehumidified air into a drying chamber at different places in the length of said chamber, the introduction of the preheated substantially dry air into the chamber at other different places in the length thereof, the rapid venting of the heated humidified air and of the heated substantially dry air from the drying chamber, and the movement of the article to be treated progressively through the zones of heated humidified air and heated substantially dry air thus created in the drier.

10. A leather drying process which comprehends the introduction into a first drying zone of a rapidly flowing current of moderately preheated and prehumidified fluid having a regulated speed of flow within said portion of the drier and regulated also as to its volume, heat and humidity, and also comprehends the introduction into a second drying zone of a rapidly flowing current of preheated substantially dry air similarly regulated with respect to its speed of flow within the drier and to its volume and temperature, the venting of the fluid from both portions of the drier at a speed which induces a rapid flow thereof within the drier, and the movement of the leather to be dried progressively through these zones.

11. A leather drying process which comprehends the introduction into one portion of a drier of air having a humidity of approximately 70-75 degrees and a temperature of approximately 90-95 degrees F., the introduction into another portion of the drier of substantially dry air having a temperature of approximately 140-145 degrees F., the inducing of a rapid flow of these airs within the drier and the movement of the article to be dried progressively through the zones of rapidly flowing air thus created in the different portion of the drier.

12. A leather drying process which comprehends the introduction into one portion of a drier, at a place intermediate the length of said portion, of preheated air having a humidity of approximately 70-75 degrees under conditions which will induce, within said portion of the drier, a rapid flow of said air and a temperature of approximately 80-85 degrees F. at the ends of the portion of the drier and approximately 90-95 degrees F. at a place intermediate said ends; and also comprehends the introduction into another portion of the drier, at a place intermediate the length thereof, of a substantially dry air, under conditions which will induce within said portion, a rapid flow of said air and temperatures of from about 120-125 degrees F. at the ends of said portion of the drier and about 140-145 degrees F. intermediate said ends; and the movement of the article to be dried progressively through the zones of rapidly flowing air thus created in the different portions of the drier.

13. A drying process which comprehends

the creation within a drier of a zone of rapidly flowing heated humidified air, a zone of rapidly flowing substantially dry air and a second zone of rapidly flowing heated humidified air, and the movement of the article to be dried through these zones, successively.

14. The process of drying or conditioning partially completed shoes, forming steps in the manufacture of the shoes, said process comprehending the conveyance of the shoes along a defined path one portion of which is through a covered chamber, the introduction into said chamber of a desiccating current of air which has been previously humidified and moderately heated, and a later portion of which path is through a second covered chamber supplied with a current of heated air having less humidity and higher temperature than the air in the first mentioned chamber, together with the regulation of the temperature, humidity, volume and speed of flow of the conditioning airs to effect a partial drying without sealing the pores of the leather in the first mentioned chamber and a further drying in the second chamber without danger of breaking down the structure of the leather, and to leave the shoes in condition for immediate further operations thereon.

15. The process of drying or conditioning partially completed shoes, forming steps in the manufacture of the shoes, which comprehends the conveyance of the shoes along a defined path, successive portions of which are through covered chambers, respectively, the introduction into the first of said chambers at different places along its length of relatively regulated desiccating currents of prehumidified and preheated air and the introduction into the other of said chambers at different places along its length of relatively regulated desiccating currents of preheated air having less humidity than that supplied to the first-mentioned chamber.

16. The process of drying or conditioning partially completed shoes, forming steps in the manufacture of the shoes, which comprehends the conveyance of the shoes along a defined path, one portion of which is through a covered chamber supplied at different places along its length with currents of rapidly flowing prehumidified and preheated air and another portion of which path is supplied at different places along its length with currents of preheated air having less humidity than that supplied to the first-mentioned chamber, together with regulation of the air in the first-mentioned chamber to cause the temperature to be lower at both ends of the chamber than at the intermediate portion thereof and similarly the regulation of the air in the second-mentioned chamber to cause the temperature to be lower at both ends than at the middle of the chamber.

17. The process of drying or conditioning

partially completed shoes, forming steps in the manufacture of the shoes, said process comprehending the conveyance of the partially completed shoes along a defined path one portion of which is through a covered chamber supplied with a flowing body of air which contains a predetermined percentage of moisture and has a temperature above that of the atmosphere and below that at 10 which the animal matter in the wet leather will be burned, to effect a partial drying of the leather without sealing the pores thereof, and a later portion of which path is through a covered chamber supplied with a flowing 15 body of air having less humidity than the air in the first chamber to further deprive the leather of its contained moisture.

18. The process of drying or conditioning partially completed shoes, forming steps in 20 the manufacture of the shoes, said process comprehending the conveyance of the partially completed shoes along a defined path one portion of which is through a first covered chamber supplied with a flowing body of 25 air which contains a predetermined percentage of moisture and has a temperature above that of the atmosphere and below that at which the animal matter in the wet leather will be burned, to effect a partial drying of 30 the leather without sealing the pores thereof and a later portion of which path is through a covered chamber supplied with a flowing body of air having less humidity and higher temperature than the air in the first 35 chamber to further deprive the leather of its contained moisture.

19. The process of drying or conditioning partially completed shoes, forming steps in the manufacture of the shoes, said process 40 comprehending the conveyance of the previously wetted partially completed shoes along a defined path, one portion of which is through a first covered chamber supplied with a flowing body of humid air whose temperature and humidity are regulated to create a 45 drying zone the atmospheric conditions in which will be characterized by a moderate heat at the entrance end of the zone and by a somewhat greater heat further along in 50 the zone end at all places in the zone will be such that the animal matter in the leather will not be burned and the pores of the leather will not be closed; and a later portion of which path is through a second covered chamber supplied with a flowing body of air whose 55 temperature and humidity are regulated to create an atmospheric condition by which moisture remaining in the shoes after the latter have passed through the first zone is 60 removed and the shoes left in condition for further manipulative steps.

20. The process herein described of drying or conditioning partially completed shoes, forming steps in the manufacture of the shoes, 65 which comprehends the conveyance of the

wetted shoes along a defined course, successive portions of which are through a first drying chamber and a second drying chamber, the subjection of the shoes while passing through the first chamber to the action of 70 a desiccating current of air which has been pretreated in respect of temperature and humidity, the regulation of said air to cause a predetermined increase in temperature and decrease in humidity from the place at which the shoes enter the chamber toward the place at which they leave said chamber, calculated to partially dry the leather without burning the animal matter therein or closing the pores thereof, and then the removal of the remaining moisture by the subjection of the shoes while passing through the second chamber to the action thereon of a second desiccating current of preheated air of increasing temperature from the entrance end of the chamber toward the discharge end thereof. 80

21. The process of drying or conditioning partially completed shoes which comprehends the conveyance of the wetted and partially completed shoes along a defined path and their subjection while traversing said path to the effects of flowing bodies of air in moisture transferring relationship with the shoes and which bodies of air are regulated in respect of heat and humidity to form atmospheric conditions such that the shoes pass through a drying zone characterized by a humid condition, and by a moderate temperature at the place where the shoes enter the zone and by a substantially gradual increase 95 in temperature to a place further along in said zone, predetermined to effect a partial drying of the shoes without burning the animal matter in or sealing the pores of the leather, and thereafter pass through a second drying zone characterized by lesser humidity and higher temperature than the body of air in the first zone and by a substantially gradual increase in the temperature to a place further along in the zone. 100

22. The process of drying or conditioning partially completed shoes which comprehends the conveyance of the wetted and partially completed shoes along a defined path and their subjection while traversing said path to the effects of flowing bodies of air in moisture transferring relationship with the shoes and which bodies of air are regulated in respect of heat and humidity to form atmospheric conditions such that the shoes pass through a drying zone characterized by a humid condition and by moderate temperature at the places where the shoes enter and leave said humid zone and by a higher temperature of substantially gradual increasing and decreasing nature between said places, and thereafter pass through a second drying zone of substantially dry air whose temperature is higher than that of the air in the first zone and increases substantially gradually 115 120 125 130

from the place at which the shoes enter the zone to a place further along in the zone and decreases substantially gradually from the latter place to the shoe exit end of the zone.

23. The process of drying or conditioning 5 partially completed shoes, forming steps in the manufacture of the shoes, said process comprehending the conveyance of the previously wetted partially completed shoes along a defined path and subjecting such 10 shoes while moving along a predetermined part of such path to the action thereon of a desiccating current of air having a predetermined percentage of humidity calculated to remove moisture from the shoes without closing 15 the surface pores thereof, and thereafter subjecting the same shoes, while traversing another part of their path to the action of a second desiccating current of air characterized 20 by lesser humidity and higher temperature than the temperature and humidity of the current to which the shoes were previously subjected.

24. The process herein described of drying 25 or conditioning partially completed shoes, forming steps in the manufacture of the shoes, which comprehends the conveyance of the shoes along a defined path from operative to operative and portions of which path are through covered chambers respectively containing 30 rapidly flowing bodies of desiccating airs of which that in the chamber first traversed by the previously wetted shoes contains percentages of heat and humidity predetermined to cause a partial drying of the shoes without burning the animal matter contained 35 in the leather and without sealing the pores of the leather, and the air in the chamber later traversed by the shoes is of lesser humidity and higher temperature than that in the first mentioned chamber and deprives the 40 shoes of contained moisture.

25. The process herein described of drying or conditioning the soles of partially completed 45 shoes while the shoes are in motion from an operative who performs one operation to an operative who performs another operation in the manufacture of the shoes, said process forming steps in the manufacture 50 of the shoes, and including the creation within an appropriate drying chamber of a rapidly flowing current of preheated and prehumidified air and the creation within another appropriate drying chamber of a rapidly 55 flowing current of air having higher temperature and less humidity than the air in the first mentioned chamber: the movement of said partially completed shoes through said chambers in moisture transferring relationship 60 with said currents: and the regulation of the currents and duration of time in which the shoes remain in each of the same to cause a drying of the soles without burning and without sealing the pores of the leather by 65 partially drying them in a moderately heated

humid and non-saturated atmosphere by which they are prepared for the action of the hotter and drier air of the second chamber.

26. The process herein described of drying or conditioning partially completed shoes, 70 whose soles have been wet as a step in the manufacture of the shoes and which drying or conditioning process forms additional steps in the manufacture of the shoes and comprehends the conveyance of the shoes along a 75 defined path from operative to operative and successive portions of which path are through a first and a second covered chamber, the subjection of a first flowing body of air to heating and humidifying agencies to raise its 80 temperature and its humidity content to predetermined percentages calculated to be below that at which wet leather to be in contact therewith will be burned or will have its pores closed, the causing of a rapid flow of 85 this preheated and prehumidified air through the chamber first traversed by the previously wetted shoes, the heating without humidification of a flowing body of air to a higher 90 temperature than that of the first mentioned body of air, the causing of a rapid flow of 95 this preheated non-humidified body of air through the second covered chamber, and the regulation of the speed of movement of the shoes within the chambers to cause their retention in contact with said first body of air for a sufficient time to partially dry and prepare them for the action of the higher and drier second body of air without injury by the latter and in contact with the second body 100 of air for a sufficient time to substantially complete the drying operation.

In testimony whereof we affix our signatures.

MORRIS U. BURNHAM.
GEORGE M. ARGABRITE.
